United States Patent Office.

GEORGE RIEMER, OF FAYETTE, NEW YORK.

Letters Patent No. 70,744, dated November 12, 1867.

IMPROVEMENT IN HARVESTERS.

The Schedule referred to in these Letters Patent and making part of the same.

TO ALL WHOM IT MAY CONCERN:

Be it known that I, GEORGE RIEMER, of Fayette, in the county of Seneca, and State of New York, have invented a certain new and useful Improvement in Harvesters; and I do hereby declare that the following is a full and exact description thereof, reference being had to the accompanying drawings, making part of this specification.

Figure 1 is a side elevation of my improved machine.

Figure 2 is a rear sectional elevation.

Like letters of reference indicate corresponding parts in both figures.

My improvement belongs to that class where a zigzag grooved wheel is employed, with the end of the pitman or a connection resting in the groove, for giving an accelerated motion to the sickle.

The invention consists in combining with such a wheel, of peculiar form, and resting on an independent shaft, a friction-roller for holding the sickle-bar in place under the accelerated motion, and lessening the friction, as hereinafter set forth.

As represented in the drawings, A is the main frame, and B the driving-wheel of a harvester. To the driving-wheel is secured a spur-gear, C, which gives motion to a pinion, D, on a shaft, E. To the end of this shaft is secured a wheel, G, in such a manner as to be removable, being shown as simply keyed on. This wheel is provided with a projecting rim or flange, a, on the inner side of which is cut the zigzag groove b, having fitting therein a small roller or bearing, c, of the sickle-bar H. Thus, as the wheel is revolved, the sickle-bar receives a rapid reciprocating motion. Near the grooved wheel a friction-roller, I, is secured to the finger-beam, under which roller, and between it and the finger-beam, runs the sickle-bar, being thus retained closely in place.

The driving-wheel itself ordinarily forms the zigzag wheel, in which case only a slow motion of the sickle is attained. In my case, by gearing to the shaft E, I gain a very rapid motion. In this rapid motion the sickle-bar is liable to derangement and misplacement, and also to great friction, which difficulties I obviate in a great degree by the employment of the friction-roller, as before described. This roller is essential under these circumstances, otherwise the motion will be so great as really to make the cutting apparatus inoperative, or to break the parts. This feature is one of much importance.

The making of the grooved wheel removable from its shaft enables me to apply one of larger or smaller size, at pleasure, to vary the motion. The projecting flange a of the wheel houses the groove and the bearing of the pitman which fits therein, so as to protect from the weather and from grass that might otherwise clog the parts.

I am aware that zigzag grooves, for giving an accelerated motion to the sickle, have before been employed; such, broadly, I do not claim.

What I claim as my invention, and desire to secure by Letters Patent, is—

The combination, with the sickle-bar H and grooved wheel G, provided with the rim a, and made removable from its shaft, of the friction-roller I, arranged and operating in the manner and for the purpose herein set forth.

In witness whereof I have hereunto signed my name in the presence of two subscribing witnesses.

GEORGE RIEMER.
